CLAIM

The ornamental design for a walking stick or similar article, as shown and described.

DESCRIPTION

FIG. 1 is a top plan view of a walking stick or similar device showing my new design;

FIG. 2 is a front elevational view thereof;

FIG. 3 is a bottom plan view thereof;

FIG. 4 is an enlarged fragmentary view thereof;

FIG. 5 is a top plan view of a second embodiment of that shown in FIG. 1;

FIG. 6 is a front elevational view thereof;

FIG. 7 is a bottom plan view thereof; and

FIG. 8 is an enlarged fragmentary view thereof.
